PORTABLE ELECTRIC FLOOR MACHINE

William E. Holt, 651-657 20th St., Oakland, Calif.

Filed Dec. 16, 1959, Ser. No. 58,689

Term of patent 14 years

(Cl. D9—2)

FIG. 1 is a front perspective view of a portable electric floor machine, showing my new design; and

FIG. 2 is a rear perspective view thereof.

The side of the machine not shown is substantially the same in appearance as the side shown.

The dominant features of my design are the portions shown in full lines.

I claim:

The ornamental design for a portable electric floor machine, as shown and described.
